BUNCH BUILDER

Dana C. Heald, Whitinsville, Mass., assignor to
 Whitin Machine Works, Whitinsville, Mass., a
 corporation of Massachusetts

Application May 13, 1940, Serial No. 334,747

11 Claims. (Class 242—43.7)

This invention relates to spinning frames and more particularly to automatic devices for winding a bunch of thread at the base of a weft bobbin to be used in an automatic weft replenishing loom. Such a bunch is provided to form the initial winding on a weft bobbin, and is wound with a very short traverse. The bunch should contain a carefully limited length of thread, so that, when the regular winding on the bobbin is exhausted and weft replenishment is indicated, the bunch will supply just enough additional weft thread to prevent complete weft exhaustion before weft replenishment takes place.

It is the general object of my invention to provide an improved and simplified mechanical construction in a bunch builder, and to provide a bunch builder which is very reliable in operation and economical to manufacture.

A further object of my invention is to provide a bunch builder in which the length of thread wound in the bunch may be easily varied and accurately controlled, and in which the location of the bunch with respect to the regular winding may be changed as desired.

My invention further relates to arrangements and combinations of parts which will be herein-after described and more particularly pointed out in the appended claims.

A preferred form of the invention is shown in the drawings, in which

Fig. 1 is a partial front elevation of a spinning frame embodying my improvements, with certain parts shown in section;

Fig. 2 is a side elevation, looking in the direction of the arrow 2 in Fig. 1;

Fig. 3 is an enlarged front elevation of the bunch builder, partly in section;

Fig. 4 is a view similar to Fig. 3 but with certain parts shown in a different relation;

Fig. 5 is a detail sectional plan view, taken along the line 5—5 in Fig. 3; and

Fig. 6 is a view of a bobbin with a bunch wound thereon.

Referring to the drawings, I have shown portions of a spinning frame which is in general of the usual type and which comprises an end frame member 10 (Fig. 1), a spindle rail 11 supporting a plurality of spindles 12, and a ring rail 14 mounted on lifter rods 15 and supporting a series of spinning rings 16. Bobbins B are mounted on the blades of the spindles 12, and threads T are wound on the bobbins B after passing through the usual ring travelers 17.

The lifter rods 15 are engaged by studs 20 on lifter levers 21 (Fig. 1) mounted on pivoted cross

shafts 22 provided with heavy counterweights W which overbalance the weight of the ring rails 14 and rings 16. An arm 24 is fixed on one of the cross shafts 22 which support the levers 21, and is connected by a chain 25 to a builder lever 26. A series of lifter levers 21, arms 24 and shafts 22 are provided at spaced intervals along the spinning frame, and successive arms 24 are connected by links 28 for simultaneous movement.

The chain 25 (Fig. 2) is connected to a winding roll 30 actuated by a ratchet wheel 31 and worm wheel 32 on a short shaft 33. The shaft 33 is turned manually when winding down the ring rail at the time of doffing, and is intermittently advanced by the usual ratchet pawl to gradually shift the range of traverse of the ring rail upward on the bobbins during the winding operation.

The builder lever 26 is provided with a cam roll 35 (Fig. 1) engaged by a builder cam 36 mounted on a cam shaft 37 rotating in a bearing 38 in the end frame 10 and driven through a gear 39 from any suitable driving mechanism.

The parts thus far described are of the usual type and in themselves form no part of my present invention.

I will now describe my improved bunch builder, by which the traverse of the ring rails 14 is controlled for winding a bunch X at the base of a bobbin B, as shown in Fig. 6.

For this purpose, I provide a fixed stand 40 (Fig. 1), adjustably mounted on a bracket 41 which may be clamped to a stud 42 projecting laterally from the end frame 10. At its upper end, the stand 40 provides a fixed bearing 43 for an extension 44 of the cam shaft 37. The stand 40 also provides upper and lower bearings 47 and 48 (Fig. 3) in which an upright shaft 50 is rotatable and also freely slidable from the position shown in Fig. 4 to the position shown in Fig. 3 and vice-versa.

A bevel pinion 51 (Fig. 3) fixed to the upper end of the shaft 50 engages a bevel pinion 52 on the cam shaft extension 44 when the shaft 50 is in raised position, but clears the pinion 52 when the shaft 50 is in lowered position.

A flange plate 55 (Fig. 3) is mounted on a hub 56 secured to the shaft 50 by a screw 57. The flange 55 also has an upward hub extension 58 which engages the under side of the fixed bearing 47 and limits upward movement of the shaft 50 and bevel pinion 51.

A latch 60 (Fig. 3) is mounted on a fixed pivot 61 in the stand 40 and is provided with a lug 62 adapted to snap under the flange 55 under

the influence of a spring 63 when the flange 55 and associated parts are raised above the lug 62. The latch 60 thereafter holds the flange 55 and associated parts in raised position until the flange is rotated to bring an opening 64 in the edge thereof into alignment with the lug 62, whereupon the flange 55 will be released and the flange and associated parts move downward until the hub of the pinion 51 engages the top surface of the bearing 47, as will be herein-after explained.

The flange 55 is also provided with a depending sleeve 70 on which a bunch-building cylindrical cam 71 is secured. As shown in the drawings, the lower end of the cam 71 is formed with a series of wave-like portions or scallops 72 which are of much less depth than the corresponding portions of the builder cam 36.

A coil spring 73 (Fig. 3) is mounted on the shaft 50 inside of the sleeve 70 and cam 71, with the upper end of the spring fixed in the hub 56 of the flange 55, and with its lower end inserted in a hole in a bearing collar 74 which may be secured in adjusted position in the lower bearing 48 by a screw 75. By loosening the screw and turning the collar, the tension of the spring may be adjusted.

The spring applies tension to the shaft 50 and associated parts which tends to rotate the shaft and cam in the direction of the arrow *a* in Fig. 3 and which returns the cam to initial position when the cam is free to rotate. This initial position is determined by a screw 76 which may be inserted in any one of a series of holes 77 in the sleeve 70 and which engages a stop 78 on the stand 49. The stop 78 is preferably a spring or a piece of rubber or some other slightly yieldable material.

A bunch-building roll 80 (Figs. 3 and 5) is positioned to engage the cam 71 and is mounted on a stud 81 fixed in the lower end of a bar 82 vertically slidably in guideways 83 formed within the stand 49. The lower end of a link 90 is pivoted to the outer end of the stud 81, and the link is slotted at its upper end, as indicated at 91 (Fig. 3), to receive a stud 92 freely slidable vertically in the slot 91. The stud 92 extends through a slot 93 in the upper end of a bracket 94 and is secured thereto by a nut 95. The stud 92 may be adjusted vertically in the slot 93 but has no movement therein during the operation of the machine. The bracket 94 is clamped by a bolt 97 to the side of the builder lever 26, previously described. A counterweight W' (Fig. 2) is provided on the builder lever 26.

Having described the details of construction of my improved bunch builder, I will now describe the operation of the various parts in the winding of a bunch on a weft bobbin.

The bunch building parts are shown in Fig. 4 in the idle position which they normally occupy during the regular winding of a bobbin, and with the bevel pinions 51 and 52 disengaged. After winding is completed, the operator presses downward on a foot-pedal 100 (Fig. 1) and winds down the chain 25 by manually rotating the worm shaft 33 (Fig. 2).

During the regular winding, the bunch building cam roll 80 has moved freely in an elongated vertical slot 102 (Fig. 3) formed in one side of the cylindrical cam 71 and the cam supporting sleeve 70. During such regular winding, the tension spring 73 presses the left-hand edge 104 of the slot 102 against the roll 80, which binds the slide or bar 82 in its guideways 83, so that

the slide remains raised while the stud 92 moves idly in the slot 91.

As soon as the lever 21 is depressed far enough to allow the builder lever 26 to move downward 5 and bring the roll 80 below the lower end of the cam 71, the spring 73 will rotate the cam in the direction of the arrow *a* in Fig. 3 until the screw 76 engages the stop 78, at which point the roll 80 will be out of alignment with the vertical slot 102.

When downward pressure on the builder lever is then released, the counterweights W and W' swing the builder lever 26 and bracket 94 upward. The stud 92 will then engage the upper 15 end of the slot 91, the link 90 will be lifted, and a bunch building cam roll 80 will be moved up against the cam 71. This slides the cam 71 and the shaft 50 upward until the hub portion 56 of the flange 55 engages the lower face of 20 the upper bearing 47, with the pinion 51 meshing with the pinion 52. When the pinions 51 and 52 are in mesh, rotation of the sleeve 70 will commence in the direction of the arrow *b* in Fig. 4.

25 The latch 60 then snaps under the flange 55 and holds the parts in operative relation, with the cam 71 rotated from the regular cam shaft 37 and with the regular cam roll 35 clearing the builder cam 36.

30 The builder lever 26 and the ring rails connected thereto will now be given a series of short vertical reciprocations which will cause the weft threads to be in the form of a bunch X (Fig. 6). The winding of the bunch will continue 35 until the shaft 50 and cam 71 has been rotated sufficiently to bring the roll 80 substantially in alignment with the upright vertical slot 102 in the cam 71 and sleeve 70. The relieved edge or let-off portion 106 of the cam 71 allows the roll 80 to be eased into the slot 102. Before the roll 80 leaves the edge 106, the cam roll 35 will be engaged by the regular cam 36 and the regular winding of the bobbin thereafter takes place.

When the roll 80 and the slot 102 are exactly 45 aligned, the lug 62 of the latch 60 will also be in alignment with the opening 64 in the flange 55, whereupon the cam 71 and associated parts return by gravity to the lowered position shown in Fig. 4, with the pinions 51 and 52 out of mesh.

50 The position of the bunch relative to said regular winding may be varied by changing the position of the stud 92 in the bracket 94 and thus varying the vertical position of the roll 35 relative to the builder cam 36 during the bunch building operation.

55 If the stud 92 is adjusted near the upper end of the slot 93, the roll 35 will entirely clear the cam 36 and the bunch will be wound below the lower limit of regular winding traverse. If the stud 92 is adjusted toward the lower end of the slot 93, the bunch X (Fig. 6) will be covered by the lower portion of the regular winding Y when the regular winding is commenced.

In the latter case, the movement of the builder lever 26 is more or less under the control of the builder cam 36 as the points of the cam pass the roll 35, even during the winding of the bunch, but the bunch builder cam 71 prevents the lever 26 following the cam 36 for the usual long traverse.

70 The length of thread placed on the bobbin during the winding of the bunch is determined by the location of the screw 76 in the sleeve 70. By placing the screw 76 in different holes 77, the 75 amount of rotation of the cam 71 required to align

the roll 80 with the slot 102 may be increased or decreased at will, thus directly varying the length of thread wound in the bunch.

The cam 11 is detachably secured to the sleeve 70, so that the cam may be conveniently removed and replaced by a cam of different design to vary the cross winding of the bunch as may be desired and to increase or decrease the number of reciprocations of the ring rails while a given length of thread is being wound on the bobbins.

My improved bunch builder is much more simple in construction than many of the devices heretofore proposed for bunch winding, and all of the parts are of relatively heavy construction and well adapted for prolonged use. Furthermore, the adjustments for varying the position of the bunch and also for varying the length of thread in the bunch are both very easily understood and easily made, and the mechanism contains no parts which require careful adjustment for satisfactory performance.

Having thus described my invention and the advantages thereof, I do not wish to be limited to the details herein disclosed, otherwise than as set forth in the claims, but what I claim is:

1. In a spinning frame having a continuously rotated builder cam and a builder lever normally oscillated thereby, in combination, a slideable shaft, a cylindrical edge cam mounted on said shaft and having a deep axially-extending recess at one point in its periphery, driving connections for said slideable shaft, one element of said driving connections being mounted on said slideable shaft and being normally axially displaced from driving relation to the other element of said connections, said edge cam being rotated when said shaft is moved axially and said driving connections are engaged, an auxiliary cam roll engaged by said edge cam and connected to give said builder lever relatively short oscillations to wind a bunch as said slideable shaft is rotated, and said builder cam being rendered effective to control said builder lever when said auxiliary cam roll enters said deep recess and moves idly therein.

2. The combination in a bunch builder as set forth in claim 1, in which automatic means is provided to determine the initial angular position of the slideable shaft and edge cam and to thereby determine the size of the bunch.

3. The combination in a bunch builder as set forth in claim 1, in which automatic means is provided to determine the initial angular position of the edge cam and to thereby determine the size of the bunch, and in which said automatic means is manually adjustable to vary the length of yarn wound in the bunch.

4. The combination in a bunch builder as set forth in claim 1, in which said edge cam is provided with a circular series of tapped holes and with a screw insertable in a selected hole, and in which a fixed stop is positioned for engagement by said screw to determine the initial angular position of said edge cam and to thereby determine the size of the bunch.

5. The combination in a bunch builder as set forth in claim 1, in which automatic means is

provided to determine the initial angular position of the slideable shaft and edge cam and to thereby determine the size of the bunch, and in which a torsion spring is provided to return said shaft and cam to initial angular position when free to turn.

6. The combination in a bunch builder as set forth in claim 1, in which means is provided to vary the vertical relation of the lower ends of the bunch winding and the regular winding.

7. The combination in a bunch builder as set forth in claim 1, in which retaining means is provided to hold said slideable shaft in operative axial position until said shaft reaches a predetermined angular position.

8. The combination in a bunch builder as set forth in claim 1, in which said shaft has a flange fixed thereon and provided with a peripheral recess, and in which a latch is mounted on a fixed pivot and automatically engages said flange when said slideable shaft is moved to engage said driving connections, and said flange and shaft being thereafter released when said latch enters said recess.

9. The combination in a bunch builder as set forth in claim 1, in which the driving connections for the slideable shaft comprise a bevel pinion on said shaft and a bevel pinion rotatable with said builder cam, said pinions being engageable by upward movement of said slideable shaft and being disengageable by downward movement thereof.

10. In a spinning frame having a continuously rotated builder cam and a builder lever normally oscillated thereby, in combination, a bevel pinion rotatable with said builder cam, a slideable shaft, a cylindrical edge cam and a bevel pinion both mounted on said shaft, said cam having a deep axially-extending recess at one point in its periphery, said edge cam being rotated when said shaft is moved vertically and said bevel pinions are engaged, an auxiliary cam roll engaged by said edge cam and connected to give said builder lever relatively short oscillations to wind a bunch as said slideable shaft is rotated, and said builder cam being rendered effective to control said builder lever when said auxiliary roll enters said deep recess.

11. In a spinning frame having a continuously rotated builder cam and a builder lever normally oscillated thereby, in combination, a bevel pinion rotatable with said builder cam, a slideable shaft, a cylindrical edge cam and a bevel pinion both mounted on said shaft, said cam having a deep axially-extending recess at one point in its periphery, said edge cam being rotated when said shaft is moved vertically and said bevel pinions are engaged, an auxiliary cam roll engaged by said edge cam and connected to give said builder lever relatively short oscillations to wind a bunch as said slideable shaft is rotated, said shaft and edge cam moving downward to disengage said bevel gears when said auxiliary roll enters said deep recess, and said builder lever being simultaneously restored to the operative control of the regular builder cam.

DANA C. HEALD.
